EX

No. 11,522,

Nov. 18, 1879

Design No. 11,522, dated November 18, 1879;
[Term of patent 3½ years.]

UNITED STATES PATENT OFFICE.

JOHN T. WEBSTER, OF FLUSHING, NEW YORK, ASSIGNOR TO THE READ
CARPET COMPANY, OF BRIDGEPORT, CONNECTICUT.

DESIGN FOR CARPET.

Specification forming part of Design No. 11,522, dated November 18, 1879; application filed October 15, 1879.
[Term of patent 3½ years.]

To all whom it may concern:

Be it known that I, JOHN T. WEBSTER, of Flushing, in the county of Queens and State of New York, have invented a new Design for Carpets; and I do hereby declare the following, when taken in connection with the accompanying photographic illustration, to be a full, clear, and exact description of the same, and which said illustration constitutes a part of this specification, and represents a portion of a carpet, showing one complete figure.

This invention relates to a design for carpet; and it consists in the pattern, as shown in the accompanying illustration, and as hereinafter described.

The ground is made up of a series of fine or narrow transverse stripes.

The figure which constitutes the special fea-

ture of the design represents two pilasters, with a wall between, crowned with a balustrade extending from one pilaster to the other, and the two pilasters surmounted by vases, from each of which springs a floriated vine branching to the right and left, but meeting over the balustrade, and a vine from each trailing downward over the pilasters. In the center is a floriated vine, represented as hanging over the balustrade and running down onto the wall.

I claim—

The design for carpet herein described, and shown in the accompanying illustration.

JOHN T. WEBSTER.

Witnesses:

H. B. ADAMS,
J. R. KEPPELER.
